UNITED STATES PATENT OFFICE.

ALBERT JOHN MEIER, OF GLENDALE, MISSOURI.

PURSE.

1,138,882.

Specification of Letters Patent. Patented May 11, 1915.

Application filed June 8, 1912. Serial No. 702,099.

To all whom it may concern:

Be it known that I, ALBERT JOHN MEIER, a citizen of the United States, and residing at Glendale, in the county of St. Louis and State of Missouri, have invented certain new and useful Improvements in Purses, of which the following is a specification.

This invention relates to purses and like devices, and more particularly to coin purses. 10 One of the objects of this invention is to provide a purse which may be readily opened to expose the contents thereof so as to permit their removal, and which when closed will securely hold the contents therein 15 and form a substantially flat compact receptacle.

Another object is to provide a device which will be simple in its construction and operation, and further objects will appear 20 from the detail description taken in connection with the accompanying drawings in which:

Figure 1 is a plan view of a purse forming the subject matter of this invention, 25 the purse being shown closed, Fig. 2 is a section on the line 2—2 Fig. 1, Fig. 3 is a section on the line 3—3 Fig. 1, Fig. 4 is a plan view showing the purse open, Fig. 5 is a section on the line 5—5 Fig. 4, Fig. 6 is 30 a detail perspective view of the spring, Fig. 7 is a detail perspective view showing another form of spring, and Fig. 8 shows details illustrating another embodiment of this invention.

Referring to the accompanying drawings, and more particularly to Figs. 1 to 6 inclusive, 35 12 designates a body or cover made of flexible material such as thin leather. This body or cover is doubled over and 40 formed or shaped so as to form when closed a flat oval receptacle as shown in Figs. 1 and 2. This receptacle is slit along one side or face as shown at 13 to form an expansible opening as hereinafter described. The body 45 may be formed of a single piece of leather shaped as shown, or it may be formed of a plurality of pieces glued or sewed together. When formed of a plurality of pieces the seam may lie along the lines 3—3, or 2—2 50 Fig. 1, or the body may be formed of two oval-shaped pieces seamed along their outside edges. A strip of leather or like flexible material 14 is secured to the inside face of the body, and this strip is slit to form two 55 lips extending along the lips of the slit 13.

The thickness of the strip decreases from the center toward the ends as shown in Figs. 3 to 5 inclusive. An oval-shaped leaf or bowed spring comprising two pieces 15 jointed at 16 is located inside of the receptacle and bears at its ends against the ends of the receptacle body, leaving the sides of the spring out of contact with the side edges, as shown in Figs. 1 and 3. The spring is so constructed and proportioned 60 that it will tend to elongate longitudinally, and the ends will therefore bear yieldingly against the ends of the receptacle body. This will tend to hold the slit 13 closed as there is an outward pull along the line of 65 the slit, and this pull will be transmitted through the strip 14.

To open the purse it is placed between the fingers and thumb as shown in Fig. 4, when a pressure upon the ends will expand the 70 opening as shown. When the purse is thus expanded, the mouth will open wide, thus exposing practically the entire interior thereof. In referring to Fig. 5 it will be noted that the lateral expansion of the 75 spring will cause the material forming the upper face of the purse to slide and pass around the spring to the lower face so as to enlarge this lower face or the bottom of the purse. This will cause the lips of the upper 80 face to stand up nearly vertical so as to form in effect a substantially flat bottomed open receptacle having nearly vertical up-standing sides. As the purse is thus wide 85 open, every part will be exposed to view 90 and will be accessible for removal of the coins. It is therefore not necessary to pour the coins out in order to remove them, but the desired coins may be readily picked from the purse. As soon as the pressure of the 95 fingers is released, the spring will automatically close the purse. In view of the fact that the lips of the strip 14 extend along the slit, the pull will be exerted through this strip, so that the edges of the 100 slit will not stretch, as would be the case if this strip were absent. The strip will also serve to retain the coins in the purse for when the purse is held up side down, the edges of the strip will stop the coins 105 from passing out of the slit.

In Fig. 6 the spring is shown as composed of two pieces jointed together at their ends. This spring may however be made of a single piece 20 as shown in Fig. 7. It is 110

also desirable to provide a spring strip 21 extending longitudinally along the lower face of the purse and connected to the ends of the spring by means of end pieces 22 secured to the spring 20 in any suitable manner. This strip 21 will serve to bow out the bottom face of the purse when expanded and will thus keep the bottom material tight.

10 Fig. 8 shows a portion of the bottom face of a purse, which in this case has the body thereof formed of two pieces 25 joined at 26 by means of a strip of leather 27 secured to the pieces by means of rows of stitches 28 or in any other suitable manner. The division line or edge 26 runs in this case along the line 3—3 Fig. 1 so that the strip 27 will run longitudinally of the receptacle. In addition to its securing function, this 20 strip will also perform the same function as the metal strip 21 in Fig. 7, *i. e.*, to bow out the bottom of the purse.

The purse when collapsed by the pressure of the fingers will form an open receptacle 25 the bottom of which, although slightly bowed out and rounded when the spring shown in Fig. 7 is used, will be a substantially flat bottom, as distinguished from and as compared with those constructions in 30 which the purse is slit along one edge.

It is obvious that various changes may be made in the details of construction without departing from this invention, and it is therefore to be understood that this invention is not to be limited to the specific construction shown and described.

Having thus described the invention what is claimed is:

1. A purse or like receptacle comprising 40 a flexible body doubled over and constructed to form a self-contained receptacle having a substantially flat bottom, and having a slit along one face thereof to form an expansible opening for the receptacle, the device being 45 collapsible to expand said slit and expose said bottom, and means constructed to normally hold said slit closed.

2. A purse or like receptacle comprising 50 a flexible body doubled over and constructed to form when extended a flat closed self-contained receptacle, and having a slit along one face thereof to form when collapsed a substantially flat bottomed open receptacle, said slit being normally closed, and said de-

vice being collapsible to expand said slit 55 and expose the bottom of the receptacle.

3. A purse or like receptacle comprising a flexible body doubled over and constructed to form a self-contained receptacle having a substantially flat bottom and having a slit 60 along one face thereof to form an expansible opening for the receptacle and an elliptical spring engaging the body at the ends of the slit constructed to hold the slit closed, the device being collapsible to expand said 65 slit and expose said bottom.

4. A purse or like receptacle comprising a flexible body doubled over and constructed to form a self-contained receptacle having a substantially flat bottom, and having a slit along one face thereof to form an expansible opening for the receptacle, and lips on the body extending along the edges of said slit, the device being collapsible to expand said slit and expose said bottom. 75

5. A purse or like receptacle comprising a flexible body doubled over and constructed to form a self-contained receptacle, and having a slit along one face thereof to form an expansible opening, and strips extending 80 along the edges of said slit, said strips decreasing in thickness from the center toward the ends.

6. A purse or like receptacle comprising a flexible body doubled over and constructed 85 to form a self-contained receptacle, and having a slit along one face thereof to form an expansible opening for the receptacle, and means for holding the slit closed when the device is extended and for bowing out the 90 face forming the bottom of the receptacle when the device is collapsed.

7. A purse or like receptacle comprising a flexible body doubled over and constructed to form a self-contained receptacle having a 95 substantially flat bottom, and having a slit along one face thereof to form an expansible opening for the receptacle, and a spring in said receptacle and extending along the edges thereof constructed to normally hold 100 said slit closed and expand said slit when the device is collapsed to expose said bottom.

In testimony whereof I affix my signature in presence of two witnesses.

ALBERT JOHN MEIER.
